UNITED STATES PATENT OFFICE

2,051,961

GOLF CLUB

Daniel T. Mears, Detroit, Mich.

Application September 30, 1935, Serial No. 42,929

1 Claim. (Cl. 273—80)

The invention relates to a golf club and more especially to a golf club shaft.

The primary object of the invention is the provision of a shaft of this character, wherein different kinds of heads can be readily and conveniently attached for changing the character of the club and also a handle is carried by this shaft so that the length of the shaft can be increased or decreased accordingly to the requirements of a player or user thereof.

Another object of the invention is the provision of a shaft of this character, wherein the head when made secure thereto will be firmly and rigidly attached so that there is no possibility of loose play between the head and the shaft when attached together.

A further object of the invention is the provision of a shaft of this character, which is simple in its construction, thoroughly reliable and efficient in its purpose, strong, durable, enabling a change in the nature of the club and also inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

30 In the accompanying drawing:

Figure 1 is a side elevation of a golf club with the shaft constructed in accordance with the invention.

Figure 2 is a fragmentary vertical longitudinal sectional view through a shaft at its handle end constructed in accordance with the invention.

Figure 3 is a fragmentary side elevation partly in section of the head of the golf club showing in detail the manner of fastening the shaft therewith.

Figure 4 is a fragmentary side elevation showing in detail the head end of the shaft.

Figure 5 is a fragmentary side elevation of a modified form of the head detached from the shaft.

Figure 6 is an enlarged sectional view on the line 6—6 of Figure 2.

Figure 7 is a sectional view on the line 7—7 of Figure 2 looking in the direction of the arrows.

Figure 8 is a sectional view on the line 8—8 of Figure 3.

Similar reference characters indicate corresponding parts throughout the several views in the drawing.

55 Referring to the drawing in detail, the golf club

comprises a head 10, this being in the nature of a driving head, a stick or shaft 11 and a handle 12, respectively, the shaft or stick being of tubular form and tapers in the direction of the head 10. The smaller end of the shaft 11 has permanently joined therewith a thimble-like coupling sleeve 13, it being streamlined in the direction of the shaft or stick and within the sleeve is received a dowel-like plug or pin 14, the same being tapered in conformity with the tapered formation 10 of the socket 15 in the said sleeve 13 and is provided with a threaded portion 16 screwed into the heel portion of the head 10 so that in this manner the latter can be separably fastened to the shaft or stick 11.

Provided in the open end of the sleeve 13 is a notch or slot 17 while anchored in the pin or plug 14 is a staple 18, the sleeve externally thereof being formed with a circular channel or groove 19 occupied by a split ring 20, which is freely rotatable within the channel or groove 19 and this ring is adapted for locking engagement in the staple 18 when the split of the said ring is aligned with the notch 17 so that the head 10 can be detachably secured with the stick or shaft 11. Thus 25 it will be apparent from Figures 1 and 3 of the drawing that varying styles of heads can be separably attached to the stick or shaft 11, this being also true with respect to wood or iron heads.

The larger end of the stick or shaft 11 is longitudinally slotted at 21 and over this end is telescoped the handle 12, which is of tubular formation having the outer closed end 22 and the opposite open end 23 which is slotted at 24 and externally threaded at 25. The slotted end is 35 slightly inwardly tapered and has adjustably threaded thereon a locking collar or sleeve 26 which when turned clamps the slotted end about the stick or shaft 11 to make the handle 12 fast upon the stick or shaft. This handle externally 40 thereof has a leather covering 26' as usual. The slotted end of the stick or shaft 11 is slidably telescoped in the handle 12 and by adjustment of the latter the length of the stick or shaft can be varied. The portion of the stick or shaft 11 to be 45 occupied by the handle 12 is of uniform diameter in cross section and the taper of such stick or shaft begins from this point in the direction of the head 10. The slotted end 21 of the stick or shaft 11 effects a frictional engagement with the 50 handle 12. The collar or sleeve 26 when adjusted effects a binding action on the slotted end of the said handle for making it fast upon the stick or shaft 11.

In Figure 5 of the drawing there is shown a 55

slight modification, wherein the head 27, only a portion thereof being shown, has formed at the heel end thereof the outwardly tapered pin or lug 28, it carrying the eye or staple 29 for accommodating the split ring 28 fitted with the stick or shaft 11.

This pin or lug 28 is adapted to be accommodated in a correspondingly tapered socket provided in the stick or shaft 11.

10 The pins 14 and 28 by reason of their tapered formation and fitting a correspondingly tapered socket therefor assure a tight joint between the head and the said stick or shaft.

It is preferable to make the head of the golf 15 club from transparent non-breakable material such as pyrachrome and the head being molded in the desired shape in the use of such material.

It will be apparent that by employing but a single shaft or stick a variety of heads are usable therewith and in this the necessity of carrying a 20 large bag for equipment will be avoided and at

the same time reducing the cost of equipment and replacement as well as saving time and trouble ordinarily encountered in removal and replacing in the bag of clubs now in use, the changing of heads being had with dispatch and in a ready and easy manner.

What is claimed is:

In a golf club, a head, a dowel-like plug threaded into said head and having a staple projecting laterally therefrom, a stick, a thimble-like coupling sleeve attached to said stick for receiving the plug and having a notch accommodating the staple, the notch opening through the outer end of said sleeve, and a split ring rotatably counter-seated externally in the sleeve, the split in said 15 ring registering with the notch to clear the staple at the split and being turnable to inter-locking engagement with the staple on rotation of the said ring upon the sleeve.

DANIEL T. MEARS. 20
